UNITED STATES PATENT OFFICE.

ALBERT BARTON, OF FINDLAY, OHIO, ASSIGNOR TO THE CLEVELAND TARGET COMPANY, OF CLEVELAND, OHIO.

DESIGN FOR A FLYING TARGET.

SPECIFICATION forming part of Design No. 27,787, dated October 26, 1897.

Application filed August 20, 1897. Serial No. 648,961. Term of patent 14 years.

To all whom it may concern:

Be it known that I, ALBERT BARTON, a citizen of the United States, residing at Findlay, in the county of Hancock and State of Ohio, 5 have invented and produced a new and original Design for Frangible Flying Targets, of which the following is a specification, reference being had to the accompanying drawings, forming a part thereof, which drawings 10 show, in—

Figure 1, a bottom plan, and in Fig. 2 a vertical central section, of a target constructed according to my design.

As shown in the drawings, the leading or 15 material features of my design consist of an inverted-saucer-shaped disk A, having a short cylindrical margin B, the lower edge b

of which is convex, and in an inclined or beveled annulus C, formed between and joining the vertical inner wall of said cylindrical 20 margin, and a horizontal annulus just above the same.

Having described my invention, what I claim as new, and desire to secure by Letters Patent, is—

The design for a frangible flying target, substantially as herein shown and described.

In testimony whereof I affix my signature in presence of two witnesses.

ALBERT BARTON.

Witnesses:

JAS. A. BOPE,
R. J. KIBLER.
